[57] CLAIM

The ornamental design for a television camera, as shown and described.

DESCRIPTION

FIG. 1 is a perspective view of the front, top and right side of a television camera showing our new design;

FIG. 2 is a front elevational view thereof;

FIG. 3 is a top plan view thereof;

FIG. 4 is a bottom plan view thereof;

FIG. 5 is a right side elevational view thereof; the left side being a mirror image thereof;

FIG. 6 is a rear elevational view thereof; and,

FIG. 7 is a perspective view similar to FIG. 1 showing the television camera as it would be used in conjunction with a computer with the elements shown in phantom lines not being a part of the claimed design.
